CLAIM

The ornamental design for an alarm clock, as shown and described.

DESCRIPTION

FIG. 1 is a front top perspective view of the alarm clock showing my new design;

FIG. 2 is an inverted rear bottom perspective view thereof;

FIG. 3 is a front elevational view thereof;

FIG. 4 is a rear elevational view thereof.

FIG. 5 is a top plan view thereof;

FIG. 6 is a bottom plan view thereof;

FIG. 7 is a left side elevational view thereof; and,

FIG. 8 is a right side elevational view thereof.

(Continued)

The broken lines showing portions of the alarm clock illustrate environmental structure only and form no part of the claimed design.
